UNITED STATES PATENT OFFICE.

ABBOTT L. ALDRICH, OF BOSTON, MASSACHUSETTS.

FIRE-ESCAPE.

SPECIFICATION forming part of Letters Patent No. 278,651, dated May 29, 1883.

Application filed February 26, 1883. (No model.)

To all whom it may concern:

Be it known that I, ABBOTT L. ALDRICH, a citizen of the United States, residing at Boston, in the county of Suffolk and State of Massachusetts, have invented certain new and useful Improvements in Fire-Escapes; and I do hereby declare that the same are fully described in the following specification and illustrated in the accompanying drawings.

This invention relates to improvements in fire-escapes of that kind which are attached to the outside of a building, and it is carried out as follows, reference being had to the accompanying drawings, where—

15 Figure 1 represents a front elevation of the fire-escape when in position for use, and Fig. 2 represents a side elevation of it in said position. Fig. 3 represents a plan view of it when in use. Fig. 4 represents a front elevation of 20 the improved fire-escape when folded up against the building when not required for use, and Fig. 5 represents a side elevation of it in said folded position. Fig. 6 represents a modification 25 of the invention, showing it as located at the side of the windows instead of in front of the windows, as shown in the former figures.

Similar letters refer to similar parts wherever they occur on the different parts of the drawings.

30 *a* represents the outer wall of a building to which my improved fire-escape is to be applied, and *b' b'' b³* represent a vertical row of windows or openings through the wall *a*, as usual.

At *c c*, just below each window, is hinged a 35 platform, *d*, which is preferably made of metal and perforated, as shown in Fig. 3, so as to obstruct as little as possible the light to the windows when said platforms *d d d d* are folded up to the position shown in Figs. 4 and 5; but

40 said platforms may be made solid if the obstruction to the light of the windows is not of importance. The outer end of each platform *d* is hinged at *e e* to the sides of an ordinary ladder, *f*, made of wood or metal, as may be required, and at the junction of the said ladder and the platforms *d d* each of the latter is provided with a cut-away portion, *d'*, to enable the occupants of a burning building to walk from the windows where the fire-escape

45 is located onto the platforms *d d*, and through the opening *d'* down on the inside of the ladder *f* when in working position, as shown in

Figs. 1, 2, and 3. The lower end of the ladder *f* is preferably provided with suitable rubber or other elastic bunters, *f' f'*, adapted to 55 rest on the sidewalk or street in front of the building, the object of such elastic bunters being to prevent a too great shock on the end of the ladder when swung suddenly to a working position. Near the upper end of the ladder *f* is attached a chain or rope, *g*, which is guided over suitable pulleys, *g' g'*, in the upper part of the wall *a*, and has attached to its lower end a suitable balance-weight, *g''*, which latter may be arranged to work on the inside 60 or outside of the building, as may be most convenient. The object of said weight *g''* is to counterbalance in part or in whole the ladder *f* and its hinged platforms *d d d d*, so that they may be raised and lowered with ease.

65 *h* is a hook-lever or similar locking device hinged to the bracket *h'*, which is secured to the wall *a*, and has attached to its inner end a pendent chain or rope, *h''*, which may extend far enough downward to enable its being 70 reached from the ground, if necessary. The hook-lever *h* serves to hook or lock on one of the rounds *f''* of the ladder, so as to retain the latter in its normal position when not in use, as shown in Figs. 4 and 5.

75 To prevent the occupants of burning buildings from falling off from the platforms *d d* when escaping thereon, I provide each of such platforms with sides or railings *i i*, which are hinged in their lower parts to the respective 80 platforms at *i' i'*, as shown. Such hinged sides or railings may be made of wood or metal, solid or perforated, to make them lighter, as may be desired. The sides or railings *i i* are hinged to the platforms *d*, so that they may be swung 85 flush or flat against the outside of the building when the fire-escape is not used and be held at right angles to the platform when in use. For the purpose of automatically raising said sides or railings *i i* and to retain them 90 in such upright position when in use I attach to the inner ends of such hinged sides *i i* chains or ropes *k k*, the upper ends of which are suitably fastened at *k' k'* to the wall *a* or suitable brackets or equivalent device thereon in such 95 manner that said chains *k k* will be drawn taut when the ladder and its platforms and sides are swung outward, and in this manner cause the sides or railings *i i* to be automati-

5 cally raised when the ladder is swung outward. As the ladder is swung back toward the building the weight of the sides *i i* will cause them to swing outward or inward, flush with the platforms, enabling me to bring the ladder with its hinged platforms and their sides or railings close up to the wall of the building when the fire-escape is not in use.

10 If it should be inconvenient to locate the fire-escape in front of a row of windows, as hereinabove described, it may be located at one side of a row of windows, as shown in Fig. 6, and to secure below the sill of each window a suitable platform, *l*, with or without railings, from 15 which the occupants might easily reach the platforms *d d d* and the ladder *f*.

15 In case of a fire it is only necessary to disengage the lock *h* from the ladder, which is done by pulling downward on the chain or rope 20 *h''*, and this may be done from any window in the row or from the ground, if so desired, and to swing the ladder with its hinged platforms and sides outward until the lower end of the ladder rests on the ground, when the occupants 25 of the burning building are immediately enabled to escape by going out of any window in the row, then onto either of the platforms *d d* and through the openings *d' d'* down on the ladder *f*. In a like manner firemen and 30 others may get access to the building by going up the ladder and onto either of the platforms leading to any desired window in the row.

The great advantage of this my improved fire-escape is that it is always ready for use at an instant's notice, that it can be reached from 35 any story in the building, and that it enables the occupants to get out of the reach of the flames and smoke from a lower window by going out to the ladder, which is located far enough—say about eight or ten feet—from the 40 building, by which all danger from smoke and fire from below is entirely avoided, and the occupant may reach the ground in safety.

45 What I wish to secure by Letters Patent and claim is—

1. In a fire-escape, the ladder *f*, hinged platforms *d d d*, hinged to the wall *a*, in combination with the hinged sides or railings *i i*, and automatic device for their operation, as herein set forth.

2. In a fire-escape, the ladder *f*, swinging platforms *d d*, with their hinged sides *i i* and chains *k k*, the balance-weight *g''*, chain *g'* and locking and releasing device *h h' h''*, all combined and arranged substantially as set forth.

50 In testimony whereof I have affixed my signature in presence of two witnesses.

ABBOTT L. ALDRICH.
